UNITED STATES PATENT OFFICE.

WILLIAM K. BENEDICT, OF NEW YORK, N. Y., ASSIGNOR TO THE CO-OPERATIVE BUILDING PLAN ASSOCIATION, OF SAME PLACE.

DESIGN FOR THE EXTERIOR OF A RESIDENCE.

SPECIFICATION forming part of Design No. 19,535, dated December 31, 1889.

Application filed December 6, 1889. Serial No. 332,829. Term of patent 3½ years.

To all whom it may concern:

Be it known that I, WILLIAM K. BENEDICT, of the city, county, and State of New York, have invented and produced a new and original Design for the Exterior of a Residence, of which the following is a specification, reference being had to the accompanying drawings, forming a part thereof.

Figure 1 represents a perspective view of a residence showing my design. Fig. 2 represents a horizontal section or plan of the first story. Fig. 3 represents a horizontal section or plan of the second story.

Similar letters of reference designate corresponding parts in all the figures.

A residence embodying my design comprises a first and second story and an attic story. The first story has at its front an octagonally-shaped bay A. Surrounding the bay A, and extending around at the side of the residence, is a porch B, the shape of the porch being substantially octagonal. At one side of the porch B, and also at the front of the residence, is a pair of steps a, leading up

to the porch. Upon one side of the residence, as shown more clearly in Fig. 1, is a rectangularly-shaped bay C, which rises from a point somewhat below the top of the first story and extends upwardly to the top of the second story. Consoles c extend between the base of the bay C and the side wall of the residence.

Extending from the roof of the residence and at the attic story is a gable D, which partly surmounts the bay C. A console d extends between the said gable and the side of the residence. At the front of the residence, above the porch B, is an octagonally-shaped bay E, surmounted by a hipped roof F. The whole is surmounted by a gable roof G, which extends from the front to the rear of the residence.

What I claim is—

A design for the exterior of a residence, substantially as herein shown and described.

WILLIAM K. BENEDICT.
